UNITED STATES PATENT OFFICE.

GEORGE B. THOMAS, OF BRIDGEPORT, CONNECTICUT, ASSIGNEE TO THE BRYANT ELECTRIC COMPANY, OF BRIDGEPORT, CONNECTICUT, A CORPORATION OF CONNECTICUT.

ELECTRIC SWITCH.

1,201,112.

Specification of Letters Patent. Patented Oct. 10, 1916.

Application filed April 29, 1913. Serial No. 764,378.

To all whom it may concern:

Be it known that I, GEORGE B. THOMAS, a citizen of the United States of America, and residing at Bridgeport, in the county of Fairfield and State of Connecticut, have invented a certain new and Improved Electric Switch, of which the following is a specification.

The present invention relates to electric switches and particularly to electric switches adapted to be used in lamp sockets, and the object of my invention is to provide an improved switch mechanism and frame in which is embodied the invention claimed by Gilbert W. Goodridge, in an application Serial Number 763,604, dated April 25, 1915, and copending herewith.

In the accompanying drawings, Figure 1 is a side elevation of the switch frame; Fig. 2 is a vertical section through the frame; Fig. 3 is an end view thereof; Fig. 4 is a plan of the blanks from which the frame is formed; Fig. 5 is an end elevation of the switch spindle; and Fig. 6 is a perspective 25 of the spindle parts detached.

The switch mechanism which the present frame is designed to support, comprises an oscillating switch piece 10, a switch actuating spring 11, a plunger 12 on which the spring is mounted, a rocker 13 for moving one end of the spring past the axis of oscillation of the switch piece in either direction, and a pair of cams 14 and 15 on the switch spindle 16 bearing against the rocker 35 on opposite sides of its axis to actuate the rocker.

The present frame comprises a base 17 perforated and screw-threaded at 18 to receive a securing screw. Integral with this base are end and side uprights 19, 20 and 21, 22, respectively. The end uprights 19 are gapped at 23 and 24 to form open bearings for the switch spindles, and the upright 19 is spaced from the ends of the side frames 21, 22 to afford a clearance space 25 in which works the cam 14. The side uprights are apertured at 26 to afford a clearance for the cam 15. Perforations 27 in the side frame permit the passage there-through of the pivot pin 28 for the rocker 13. Out-turned lugs 29 on the side uprights form journals for the switch piece 10 and these lugs are preferably rounded on their bearing surfaces to the contour of the bearing apertures 30 in the legs of the switch

piece. A pair of offset lugs 31 form stops against which the spread ends of the switch piece strike, thus limiting its upward oscillation, while forwardly projecting lugs 32 at the lower portion of the side frames form stops against which the switch piece strikes on its thus limited downward travel.

The switch spindle 16 is of non-circular cross section, and the cams 14 and 15, of identical shape, are apertured at 33 to correspond to the cross section of the spindle, and at an angle of 45 degrees to their respective long axes. This not only enables me to use a single die for striking out both cams, but the spindle is automatically retained in the frame by its end 34, the sides of which overlie the edges of the gapped bearing 24 which is of less diameter than the long cross-sectional diameter of the spindle, the latter being peripherally recessed at 35 to fit in this bearing. The assembly of the cams on the spindle is exceedingly simple. Cam 14 is first adjusted and pushed up against the circular bearing portion 36, (which in assembled position fits in bearing gap 23), the cylindrical spacing sleeve 37 is then passed over the spindle 16 and the second cam 15 adjusted on the latter at right angles to cam 14 and pushed up against the spacing sleeve, whereupon the spindle is ready for adjustment in the switch frame. It will be noted that the axis of the thumb key 38 corresponds to that of one of the cams, here cam 15, so that the key lies in either vertical or horizontal position in the "on" or "off" condition of the switch and so serves as an indicator of the switch position. The assembly of the parts in the switch frame is equally simple. The switch spindle with its cams in position, is placed in its open gap bearings 23, 24. The switch piece 10 is then sprung over the journals 29 on the side frames, whereupon the end of the plunger 12 on which the spring 11 is mounted, is passed through the cross piece at the end of the yoke forming the switch piece and the spring put under tension. The rocker and plunger head being brought into engagement, the rocker is properly positioned with relation to the perforations 27 in the side uprights and the pivot pin 28 passed through the perforations so that it rests in the bearing groove 39 of the rocker. Inasmuch as the rocker is constantly held up

against the pin 28 by the cams 14 and 15, the parts are thus simply assembled and efficiently retained in operative position.

I claim as my invention:—

5 1. In an electric switch, a switch frame having a base with integral end and side uprights projecting substantially at right angles to the base and to one side thereof, the side uprights being spaced at one end 10 from the adjacent end upright to afford a clearance for an operating cam, and the end uprights having bearings for a switch spindle.

2. In an electric switch, a switch frame 15 having a base with integral end and side uprights projecting substantially at right angles to the base and to one side thereof, the side uprights being spaced at one end from the adjacent end upright and aper- 20 tured in alinement to afford clearances for spaced operating cams, and the end uprights having bearings for a switch spindle.

3. In an electric switch, a switch frame having a base and at each end thereof an 25 upright apertured to form alined open bearing gaps, in combination with a switch spindle of non-circular cross section bearing in said journal gaps and having a reduced portion lying in one of said bearing gaps, 30 the latter being of less diameter than the long cross-sectional diameter of the spindle and means for maintaining said spindle in such angular position when at rest that the portion thereof lying beyond the reduced 35 area of the spindle engages the sides of said bearing gap and thereby holds the spindle against longitudinal displacement.

4. In an electric switch, a switch spindle of non-circular contour having its long axis 40 at an angle of substantially 45° to that of the switch key, and cams on said switch spindle at right angles to each other, one of said cams having its long axis alined with the switch key.

45 5. In an electric switch, a switch spindle of non-circular contour having its long axis at an angle of substantially 45° to that of

the switch key, and cams on said switch spindle at right angles to each other, one of said cams having its long axis alined with 50 the switch key, in combination with a switch frame having open gap bearings for said spindle, the latter being peripherally re-cessed at one of said bearings, for the purpose specified.

55 6. In an electric switch, a frame having a base with side uprights, a pin extending between said uprights, and a rocker arranged below said pin and freely pivoted thereon, substantially as described.

60 7. In an electric switch, a frame having a base with side uprights, a pin extending between said uprights, and a rocker arranged below said pin and freely pivoted thereon, said rocker having a transverse bearing 65 groove in which said pin freely lies in ex-tended position, substantially as described.

7. In an electric switch, a frame having a base with side uprights, a pin extending between said uprights, and a rocker arranged 70 below said pin and freely pivoted thereon, together with rocking means supporting said rocker from beneath and serving to main-tain the same in pivoted engagement with said bearing pin, substantially as described.

75 9. In an electric switch, a switch spindle of non-circular contour having its long axis at an angle of substantially 45° to that of the switch key, cams perforated to the con-tour of the switch spindle and at an angle 80 of 45° to the long axes of said cams, said cams being slipped over said switch spindle, spaced apart thereon and arranged at right angles to each other, one with its long axis alined with the switch key, substantially as 85 described.

In testimony whereof I have signed my name to this specification, in the presence of two subscribing witnesses.

GEORGE B. THOMAS.
